United States Patent

Des. 236,579
Patented Sept. 2, 1975

236,579

KNIFE HANDLE

George C. Morhac, Fort Wayne, Ind., assignor to
Lincoln Manufacturing Company, Inc.

Filed Mar. 6, 1974, Ser. No. 448,472

Term of patent 14 years

Int. Cl. D7—03

U.S. Cl. D7—152

FIG. 4

FIG. 5

FIG. 1 is a perspective view of a knife handle showing my new design;

FIG. 2 is a side view thereof;

FIG. 3 is a top view thereof;

FIG. 4 is an end view thereof as seen from the left of FIG. 2; and,

FIG. 5 is an end view thereof as seen from the right of FIG. 2.

The side opposite that represented in FIGS. 1 and 2 is identical to that shown. The bottom of the knife handle has the appearance and configuration shown in FIGS. 1, 2, 4 and 5.

I claim:

The ornamental design for a knife handle, substantially as shown and described.
